(57) **CLAIM**

We claim the ornamental design for a kitchen faucet, as shown and described.

DESCRIPTION

FIG. 1 is an upper perspective view of a first embodiment of a kitchen faucet according to the new design.

FIG. 2 is a lower perspective view of the kitchen faucet shown in FIG. 1.

FIG. 3 is a front view of the kitchen faucet shown in FIG. 1.

FIG. 4 is a rear view of the kitchen faucet shown in FIG. 1.

FIG. 5 is a right side view of the kitchen faucet shown in FIG. 1.

FIG. 6 is a left side view of the kitchen faucet shown in FIG. 1.

FIG. 7 is a top view of the kitchen faucet shown in FIG. 1; and,

FIG. 8 is a bottom view of the kitchen faucet shown in FIG. 1.

Those portions of the kitchen faucet which are presented in the Figures with dotted lines (‘- - -’) show unclaimed aspects of the kitchen faucet and as a result, they form no part of the claimed kitchen faucet. Further, any surface shading presented in the accompanying Figures is provided to indicate contours of the kitchen faucet and is not intended to be illustrative of the kitchen faucet’s surface finish, texture or gloss.
